United States Patent Office

Des. 214,874
Patented Aug. 12, 1969

214,874

BOTTLE

Harold J. Vanderhyde, North Merrick, N.Y., assignor to
The Procter & Gamble Company, Cincinnati, Ohio, a
Corporation of Ohio

Filed July 1, 1968, Ser. No. 12,568

Term of patent 14 years

Int. Cl. D9—01

U.S. Cl. D9—110

FIG. 1 is an elevational view of a bottle showing my new design.

FIG. 2 is an elevational view thereof as seen from the left of FIG. 1.

FIG. 3 is a top plan view thereof.

FIG. 4 to 9 inclusive are, respectively, cross sectional views taken on the lines 4—4, 5—5, 6—6, 7—7, 8—8 and 9—9 of FIG. 1.

FIG. 10 is a bottom plan view thereof.

I claim:

The ornamental design for a bottle, as shown.
